Primary Examiner — Derrick Holland*Assistant Examiner* — Janice Lim(74) *Attorney, Agent, or Firm* — Cantor Colburn LLP(57) **CLAIM**

The ornamental design for a shoe, as shown and described.

DESCRIPTION

FIG. 1 is a front, right-hand side, top perspective view of a shoe, showing my new design;

FIG. 2 is a front view thereof;

FIG. 3 is a right-hand side view thereof;

FIG. 4 is a left-hand side view thereof;

FIG. 5 is a rear view thereof;

FIG. 6 is a top view thereof; and,

FIG. 7 is a bottom view thereof.

The broken line portions of FIGS. 1–7 are included to show unclaimed subject matter only and form no part of the claimed design.
